UNITED STATES PATENT OFFICE.

GEORGE H. HAGERMANN, OF MUSCATINE, IOWA.

TRAP.

Application filed October 21, 1926. Serial No. 143,199.

The invention relates primarily to improvements in traps designed for catching rats, but such invention is by no means restricted to this particular field of use, as it 5 may be constructed in different sizes and modified if it is to be used for other purposes.

In rat traps of the general type having a horizontal base and a spring-actuated jaw 10 thereon, the bait-holding trigger is usually releasable by downward movement. Thus, when initially setting the trap, particularly when laying it upon the floor, extreme caution must be exercised to prevent the weight 15 of the trigger and weight of the bait carried thereby, from accidentally releasing the trap. It is one object of my invention to provide a new and improved trap in which this undesirable characteristic does not exist, the construction being such that the bait-holding trigger must be lifted to spring the trap, said trigger and the bait being normally supported against accidental movement by a portion 20 of the base.

25 Traps of the type above set forth, commonly employ a pivoted arm to extend over the spring-actuated jaw for the purpose of holding this jaw in set position, and it is a further object of the invention to provide a 30 new and improved construction and arrangement of parts for holding said arm in its operative position, all features being of such formation as to permit rapid, inexpensive and easy manufacture.

35 With the foregoing in view, the invention resides in the novel subject matter herein-after described and claimed, the description being supplemented by the accompanying drawing.

40 Fig. 1 is a plan view of a trap constructed in accordance with my invention, showing the same set.

Fig. 2 is an enlarged detail longitudinal section on line 2—2 of Fig. 1.

45 Fig. 3 is a vertical transverse section on line 3—3 of Fig. 2.

In the drawing above briefly described, the preferred form of construction has been illustrated, and while this construction will 50 be hereinafter specifically defined, it is to be understood at the outset, that within the scope of the invention as claimed, variations may be made.

The numeral 5 designates a base prefer- 55 ably formed from wood. Pivottally mounted upon this base, is a movable jaw 6 having an

actuating spring 7. An arm 8 is pivoted at 9 to the base to extend over the jaw 6 and hold the latter in the set position shown in Fig. 1, and novel provision is made for holding this arm in its trap-set position.

10 designates a vertically disposed sheet metal plate laterally bent at its lower end to provide an attaching foot 11 which may be secured by a screw or other fastener 12, upon the base 5. Preferably, the corners of this foot are bent downwardly to form prongs 13 which penetrate the base and hold the foot and the plate 10 against turning about the fastener 12. At its lower end, the plate 10 has integral tongues 14 which are bent laterally in the opposite direction from the foot 11 and are then curved upwardly to provide a pair of horizontally alined bearings 14.

A latch plate 15 contacts with one flat side 75 of the plate 10 and is pivoted to the latter at 16, said latch plate having a nose 17 to overlie the free end of the arm 8 to retain the latter in its trap-set position. Below this nose, the latch plate 15 is provided with an extended pointed end 18 which projects beyond one edge of the plate 10. This edge is denoted at 19 and it preferably has its upper portion inwardly offset from its lower portion as shown most clearly in Fig. 3. The 80 arm 8 occupies a position at the upper portion of this edge 19, when the trap is set, and the nose 17 projects beyond said edge portion to engage said arm, as shown.

A rock shaft 20 is mounted in the bearings 90 14 and at one end is provided with an up-standing arm 21 having a hook 22 at its upper end to engage the pointed end 18 of the latch plate 15, so as to hold the latter in operative position. The other end of the shaft 95 20 is provided with a bait-carrying arm or trigger 23 having a bait-receiving hook 24 at its free end. When the trap is set as shown in the drawing, the arm 23 rests upon the base 5 so that it and the bait are solidly 100 supported and hence they have no tendency to move by gravity. In order for a rat or the like to release the trap, he must lift the bait and in so doing, the arm 23 turns the rock shaft 20 and the latter moves the arm 21 to release its hook 22 from the end 18 of the latch plate 15.

As soon as this hook is released, the upward pressure of the jaw 6 against the arm 8, swings the latter upwardly, the plate 15 being then free to permit such swinging. The jaw 6 being thus released, is thrown over by the spring 7 to 105 110

catch and hold the rat or other animal between the jaw and base.

The invention is exceptionally simple and inexpensive, yet it will be highly efficient and in every way desirable. The details disclosed have proven to be very advantageous and they are preferably followed. However, within the scope of the invention as claimed, variations may be made.

10. I claim:

1. An animal trap having a releasing bait-carrying trigger which must be lifted to spring the trap, and means for holding said trigger against downward movement from set position.

2. In a trap, animal trapping means, means for holding said trapping means in set position, including a bait-carrying trigger mounted for upward movement to release said holding means, and a support upon which the weight of the trigger and bait are sustained when the trap is set, overcoming liability of accidental springing of the trap by the action of gravity on the trigger and bait.

3. A trap comprising a base, a spring-actuated jaw mounted thereon, an arm pivoted on the base to hold said jaw in set position, a support projecting from the base, a latch pivoted to said support for engagement with said arm to hold the latter in trap-set position, a rock shaft having a portion to engage said latch and hold the latter in operative position, said rock shaft having a bait-carrying arm which lies upon the base when the trap is set, whereby the weight of the arm and bait is sustained by said base, and mounting means for said rock shaft, said latch-holding portion of said rock shaft be-

ing releasable only by lifting of said bait-carrying arm.

4. A trap comprising a base, a spring-actuated jaw mounted thereon, an arm pivoted on the base to hold said jaw in set position, a supporting plate secured to and projecting from said base in a plane transverse to the trap-set position of said arm, said plate having bearing means whose axis is parallel to the base, a latch pivoted to one side of said plate and engageable with said arm to hold it in said trap-set position, and a rock shaft mounted in said bearing means and at one end having an arm to engage said latch and hold the latter in trap-set position, the other end of said rock shaft having a bait-carrying arm which rests upon the base when the trap is set, whereby the weight of the arm and bait is sustained by said base, said latch-holding arm of the rock shaft being releasable only by lifting of said bait-carrying arm.

5. Holding means for a jaw-holding arm of a trap, comprising a metal plate having one end bent laterally to provide an attaching foot, said plate having integral tongues at the inner end of said foot bent to form bearings disposed in alinement, a latch plate pivoted to one side of the first named plate to engage the jaw-holding arm and hold the latter in trap-set position, and a rock shaft mounted in said bearings, one end of said rock shaft having an arm to engage said latch and hold it in arm-holding position, the other end of said shaft being provided with a bait-holding arm.

In testimony whereof I have hereunto affixed my signature.

GEORGE H. HAGERMANN.
